(57) **CLAIM**

The ornamental design for an adjustable partition, as shown and described.

DESCRIPTION

FIG. 1 is a front top perspective view of an adjustable partition showing our new design;

FIG. 2 is a rear bottom perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof;

FIG. 8 is a bottom view thereof;

FIG. 9 is a front top perspective view of the adjustable partition of FIGS. 1-8 shown in an example unclaimed environment;

FIG. 10 is a rear bottom perspective view thereof;

FIG. 11 is a right side view thereof;

FIG. 12 is a left side view thereof;

FIG. 13 is a front view thereof;

FIG. 14 is a rear view thereof;

FIG. 15 is a top view thereof; and,

FIG. 16 is a bottom view thereof.

The long dash/short dash broken lines immediately adjacent to the bottom of the shaded area represent the bounds of the claimed design and form no part thereof. The pattern shown on the surfaces of the adjustable partition represents a wood grain appearance. The evenly spaced broken lines depicting the remainder of the adjustable partition show environmental features that form no part of the claimed design.
